SPECTACLE CASE

Ada I. Krieger, New York, N. Y.

Application May 26, 1948, Serial No. 146,619

Term of patent 3½ years

(Cl. D57—1)

To all whom it may concern:

Be it known that I, Ada I. Krieger, a citizen of the United States of America, and residing in the city, county, and State of New York, have invented a new, original, and ornamental Design for a Spectacle Case, of which the following is a specification, reference being made to the accompanying drawing, forming part thereof.

Fig. 1 is a front elevational view of the spectacle case, showing my new design;

Fig. 2 is an edge view of the spectacle case of Fig. 1;

Fig. 3 is a rear view of the spectacle case of Fig. 1.

The essential features of my design reside in the parts shown in full lines.

I claim:

The ornamental design for a spectacle case, substantially as shown and described.

ADA I. KRIEGER.
